UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-GEAR.

1,228,591.

Specification of Letters Patent.

Patented June 5, 1917.

Application filed September 2, 1915. Serial No. 48,589.

To all whom it may concern:

Be it known that I, JOHN F. O'CONNOR, a citizen of the United States, residing at Chicago, in the county of Cook and State of Illinois, have invented a certain new and useful Improvement in Draft-Gears, of which the following is a full, clear, concise, and exact description, reference being had to the accompanying drawings, forming a part 10 of this specification.

This invention relates to improvements in draft gears.

An object of the invention is to provide a draft gear of the friction type designed 15 more particularly to meet the special requirements as a shock absorber between a locomotive and its tender.

Another object of the invention is to provide a friction draft gear which is under 20 a high initial compression closely approximating the tractive power of a locomotive, and having a release of high capacity.

A still further object of the invention is to provide a friction draft gear so arranged 25 that the frictional resistance during a pre-determined portion of the travel of the gear remains substantially constant and thereafter, during the actuation of the gear, the frictional resistance is increased.

30 The invention, furthermore, consists in the improvements in the parts and devices and in the novel combinations of the parts and devices herein shown, described or claimed.

In the drawing forming a part of this 35 specification, Figure 1 is a longitudinal sectional view of adjacent portions of a locomotive and its tender, showing my improvement in connection therewith. Fig. 2 is an enlarged sectional view of the improved 40 gear, and Fig. 3 is a transverse sectional view taken substantially on the line 3—3 of Fig. 2.

In said drawing, 10 denotes the tender 45 and 11 a portion of the locomotive, the gap between the two being bridged by the usual pivoted floor plate 12. The gear A is mounted on the tender beneath the floor thereof, said gear abutting at its rear end, a rigid casting 13 suitably riveted to the underframe 50 of the tender. The gear is supported by means of a saddle plate 14 and tie plate 15. The locomotive is provided with a chafe casting 16 having a rounded face 17, which bears against the wedge of the friction gear, 55 said chafe casting being attached to the loco-

motive by means of a pin 18 which passes through arms 19—19 of said casting and partitions or webs 20—20 of the locomotive underframe. The locomotive and tender are coupled together by a shackle 21 having an elongated slot 22 to accommodate the pin 18 at one end and a slot 23 at its other end to accommodate the pin 24.

The gear A, as shown, comprises a friction cylinder 25 and a substantially rectangular spring cage 26, the latter having a rear wall 27 formed integrally therewith. Mounted within the spring cage are twin arranged springs 28—28, the latter having their forward ends seating against a follower 29; the latter being limited in its forward movement by an annular shoulder 30, formed at the inner end of the cylinder 25. Coöperable with the friction cylinder 25 are friction shoes 31, the latter having interposed therebetween a wedge 32, a plurality of anti-friction rollers 33, being located between the wedging faces of the shoes and wedge. Located between the inner ends of the friction shoes 31 and the follower 29, 70 is a supplemental spring follower 34. The follower 34 has an inturned annular flange 35 at its inner end which is seated in a correspondingly shaped recess 36 in the front face of the follower 29. The follower 34 75 is slidably mounted within the cylinder and at its outer end is provided with an outturned annular flange 37 which, on sufficient inward movement of the friction elements, engages and is limited in its movement by an in-turned annular flange 38, located at the inner end of the friction cylinder. Interposed between the spring follower 34 and the inwardly extending shoulders 39 on the shoes 80 is a preliminary spring 40, which is maintained under an initial compression. As shown, the follower 29 is provided with a forwardly extended post or thrust member 41, which is maintained in engagement with the wedge. Said post 41 is hollow, and is 85 adapted to receive therethrough a bolt 42, by which the friction elements, preliminary spring 40, spring followers 34 and 29 are held in assembled relation, and the spring 40 under an initial compression.

As clearly shown in the drawing, the out-turned annular flange 37 of the preliminary spring follower 34 is normally spaced from both the inner ends of the friction shoes and the annular flange 38. In practice, the 110

distance between the annular flange 37 and the adjacent ends of the friction shoes will be about one inch, and the distance between said flange 37 and the flange 38 will be about 5 one and one-half inches.

The operation is, as follows:

Upon pressure being applied to the wedge 32, the shoes and wedge, spring 40, and followers 34 and 29 will move inwardly substantially as a unit. The spring 40 being under an initial compression, a substantially constant frictional resistance will be afforded to the movement of the shoes and wedges until the flange 37 engages with the flange 10 38. During this movement, all the moving parts are, of course, resisted by the heavy springs 28-28. After the first inch and a half inward movement of the parts, that is, until the flange 37 engages the flange 38, 15 the supplemental follower 34 will be prevented from further inward movement, and as the shoes and wedge continue their inward movement for the next inch, the frictional resistance will be greatly augmented 20 as the spring 40 is compressed. Simultaneously with the increase of the frictional resistance during the last inch movement of the shoes and wedge, the wedge 32 will be resisted in its movements by the springs 25 28-28. Upon release, the heavy springs 28-28 will act directly through the follower 29 and plunger 41 on the wedge 32, thereby relieving the outward pressure on the friction shoes. As the pressure on the shoes is 30 released, the latter will move outwardly under the expansion of the spring 40, and finally the follower 29 will engage the follower 34, and the outward movement of all 35 the parts will be continued until the same 40 assume the normal position best indicated in Fig. 2 of the drawing.

Although I have herein shown and described what I now consider the preferred embodiment of my improvements, I am 45 aware that changes and modifications may be made in the details of construction and arrangement of parts without departing from the spirit of the invention, and I contemplate all such changes and modifications 50 as come within the scope of the claims appended hereto.

I claim:

1. A friction gear comprising, in combination, a friction shell, friction shoes co-operable therewith, a wedge, a main spring, a spring follower, located between said shoes and said main spring, a thrust member interposed between said wedge and said follower, and a preliminary spring interposed 55 between said shoes and said follower.

2. A friction gear comprising, in combination, a friction shell, friction shoes co-operable therewith, a wedge, a main spring, a follower, a thrust member interposed between said wedge and said follower, and 60

arranged to maintain a fixed distance between said wedge and follower at all times, and a preliminary spring interposed between said shoes and said follower, said preliminary spring, main spring, and follower all being located on the same side of the friction shoes. 70

3. A friction gear comprising, in combination, a friction shell, friction shoes co-operable therewith, a wedge, a main spring, a spring follower, a preliminary spring between said shoes and said follower, and a supplemental follower movable with said first named follower during a portion of the operation of the gear, and means for arresting the movement of said supplemental follower prior to the full movement of the gear. 80

4. A friction gear comprising, in combination, a friction shell, friction shoes co-operable therewith, a wedge, a main spring, a preliminary spring acting directly against said shoes, a follower against which one end of said preliminary spring acts directly, said preliminary spring being under an initial compression, and means for limiting the movement of said follower after a partial actuation of the gear. 90

5. A friction gear comprising, in combination, a friction shell, friction shoes and a wedge co-operable therewith, main springs at the rear of said shell, a follower for said springs, a preliminary spring interposed between said follower and said shoes, the forward end of said preliminary spring directly engaging said shoes, said preliminary spring being under an initial compression, and a plunger interposed between and engaging both said follower and said wedge. 95

6. A friction gear comprising, in combination, a friction shell, friction shoes and a wedge co-operable therewith, main springs at the rear of said shell, a follower for said springs, a preliminary spring interposed between said follower and said shoes and under an initial compression, and a plunger interposed between said follower and said wedge, said plunger being in contact with the wedge and follower both in normal position of the parts and during actuation thereof. 105

7. A friction gear comprising, in combination, a friction shell, friction shoes and a wedge co-operable therewith, twin arranged main springs at the rear of said shoes, a spring follower at the front ends of said springs, a supplemental follower located on the forward side of said spring follower and slidably relatively to said shell, a plunger extending between said main 120 spring follower and the wedge, and a preliminary spring interposed between said shoes and said followers, the wedge, shoes, preliminary spring, and followers being movable in unison during the first portion 125 of the operation of the gear. 130

of the actuation of the gear, the supplemental follower being prevented from movement during the last portion of the actuation of the gear.

- 5 8. A friction gear comprising, in combination, a friction shell, friction shoes and a wedge coöperable therewith, twin arranged main springs at the rear of said shoes, a spring follower at the front ends of said 10 springs, a supplemental follower located on the forward side of said spring follower and slidably relatively to said shell, a plunger extending between said main spring follower and the wedge, and a preliminary 15 spring interposed between said shoes and said followers, the wedge, shoes, preliminary spring, and followers being movable in unison during the first portion of the actuation of the gear, the supplemental follower

being prevented from movement during the 20 last portion of the actuation of the gear, said preliminary spring being under an initial compression.

9. A friction gear comprising, in combination, a friction shell, friction shoes coöperable therewith, a wedge, a main spring, a preliminary spring located between said shoes and said main spring, said wedge, shoes and preliminary spring all moving bodily during preliminary action of the 25 gear, and means for arresting the movement of the end of the preliminary spring remote from the shoes after a predetermined preliminary actuation of the gear.

In witness that I claim the foregoing I 35 have hereunto subscribed my name this 31st day of July, 1915.

JOHN F. O'CONNOR.
